ROAD WORKING APPARATUS

William P. Day, Cleveland Heights, Ohio

Application April 23, 1952, Serial No. 283,958

3 Claims. (Cl. 94—48)

1

The present apparatus relates to improvements in road working apparatus and more particularly to improvements in vibrating and tamping apparatus used in the building of roads and like structures.

In the construction of roads and other like surfaces a base is usually built comprising coarse aggregate material such as broken stone, slag and the like filled with fines or screening of similar materials, the base usually being built up to a desired thickness by two or more courses of filled aggregate. For some purposes, the filled aggregate structure itself is used for roadway or other surfaces supporting vehicular traffic and in other cases a bituminous surface or concrete surfacing is applied thereto. Whatever the ultimate finished form or the number of courses used the procedure in laying any given course is generally the same. The coarse aggregate is spread to a certain thickness and compacted by rolling, tamping, vibrating or other like procedures. Fines are then spread thereover and dispersed into the aggregate layer to fill the interstices thereof by tamping, rolling or vibrating operations, and, finally, the whole thickness is finally worked to the desired dimension and density by further compacting operations.

Various compacting apparatus have been used heretofore, such as the long used steam roller or the more recently introduced tamping and vibrating mechanisms. In my co-pending U. S. application, Serial No. 5,388, filed January 30, 1948, now Patent No. 2,633,781, a new and improved apparatus for such purposes has been disclosed which produces both a tamping and vibrating action on the material being worked. The apparatus therein disclosed has been successfully used to lay very thick bases of superior density as a single course of aggregate well filled with fines, in other words, bases of such thickness as hitherto it has been practical to construct only in two or more courses.

In such vibrating and tamping apparatus, particularly such as that disclosed in my aforementioned application, the present invention aims at improvements which result in greater and more uniform compaction densities with fewer passes of the apparatus over the surface being treated. The invention here disclosed comprises the combination, with the tamping and vibrating mechanism of a compacting machine, of means for statically loading the vibrating mechanism which includes an elastic suspension or support therefor.

The general object of this invention is the provision in a road working machine of mechanism

2

of the vibrating, tamping type having improved compacting action. Another object is the provision in a road working apparatus of a vibrating and tamping mechanism having static loading means elastically supported thereon. Other objects and advantages of the invention will appear from the following description of a particular embodiment thereof and the drawings wherein—

Fig. 1 is a side view of a vibrating and tamping unit of a road working machine having the loading means of this invention;

Fig. 2 is a plan view of the unit of Fig. 1; and

Fig. 3 is a fragmentary section showing details of the pivot mounting provided for the static loading means.

Though not so limited in application, this invention is shown in the drawings as embodied in a road working machine such as that disclosed in my above mentioned co-pending application, but only a transverse shoe supporting means 10 of the tractor machine and a single vibrating and tamping shoe and mechanism 11 are shown for the sake of simplicity. Preferably a plurality of tamping shoes 11 are disposed across the front 20 of the tractor unit of the machine. Each shoe 11 is connected resiliently at each side to an arm 12 by a vibration damping unit 13, and the arm in turn is pivotally supported by a bracket structure carried by the beam 10 through a set of damping units 14 and pivot shaft 14a so that vibration induced in the tractor unit by the shoe 11 is minimized. Not shown in the drawings is a retracting or elevating mechanism whereby the entire shoe mechanism 11 may be swung up from the ground about the horizontal transverse pivot shaft 14a when the vibrating mechanism is not in use. Each of the damping units 13, 14 is similar in structure to unit 38 or 39 shown in Fig. 3 and hereinafter described.

To impart to the entire shoe mechanism 11 the desired vibrating and tamping motion, an actuating unit 16 is provided thereon. Preferably this actuating unit is of the type described in my aforementioned application, having a pair of similar meshing coplanar gear wheels 17, 18, each provided with an eccentric mass 19, and driven at identical speeds in opposite directions, with the rotational relation of the weights 19 being such as to develop a reaction force vibrating the shoe in a desired direction, for example that of the straight arrow in Fig. 1. To minimize horizontal force components transmitted to support 10, the wheels 17, 18 are mounted on parallel shafts 20 disposed in a plane preferably near parallel to the plane of the supporting arms 12 and the eccentric weights 19 are disposed so

that their mass centers will pass simultaneously through the plane of the shafts developing a force resultant midway between the wheels and perpendicular to the plane of shafts 20. External to the housing of the actuating unit 16 a pulley 21, mounted on the projecting end of the shaft 20 supporting wheel 18, is driven through belting 22 by a pulley 23 mounted on a drive shaft 24, which is supported by the transverse beam 10 and in turn driven by an engine carried on the tractor.

On the top plate 30 of the actuating unit 16 a pair of bracket plates 31 is provided pivotally mounting, in a manner hereafter described, the bracket arms 32 of the loading weight or mass 33, the transverse horizontal pivot axis of the weight being disposed parallel to shafts 20 and above and intermediate the ends of the arms 12. The weight 33 is located or centered in the line of action of the reaction force resultant of the wheels, that is, the mass center thereof lies in the common plane of rotation of the mass centers of the eccentrically weighted coplanar wheels. The heavy helical spring 34 is interposed between the top plate 30 and the mass 33. To maintain this spring in proper position, one end is inserted within a recess 35 bored in the bottom of the static loading mass with the other end resting on a block 36 on top plate 30 of the actuating unit housing. Block 36 also may be recessed or provided with other means for maintaining the lower end in position. To provide a restrained, resiliently pivoting mounting for the mass 33, the pivotal connection between the brackets 31 and 32 at each side of the mass is provided by the structure shown in detail in Fig. 3. The brackets 31, 32 are provided respectively with rubber mounting units 38 and 39 similar to the units 13 and 14. Unit 38 comprises an outer cylindrical collar 40 affixed to the bracket plate 31, an inner sleeve 42, and a cylindrical rubber cushion 41 between and bonded to the outer collar and inner sleeve. Unit 39 comprises a like collar 43 on bracket plate 32, cushion 44 and sleeve 45. Between the inner sleeves 42 and 45 of each pair of units 38, 39 is inserted a spacing washer 46. Likewise a spacing tube 48 is interposed between the inner sleeves 42 of two units 33. A rod 47, extending through the four inner sleeves 42, 45 and spacing tube 48, is provided at each threaded end with washer 49 and nut 50 whereby the several inner sleeves and spacers may be drawn together in an endwise direction to prevent relative rotation. In consequence of this arrangement, the rubber cushions 41, 44 are torsionally stressed serially upon movement of the mass 33 relative to the shoe 11. Hence the upward pivoting movement of the weight is restrained by the torsional resistance of the cushions to counteract erratic movement of the weight away from coil spring 34 during dynamic operation of the shoe. With the mounting structure shown the cushions may be adjusted to pre-stressed condition to increase the resistance to upward swinging of the weight.

In one application of this invention six shoe units of the type shown in the drawings were mounted on beam 10 across the front of a tractor unit. Each shoe, about 2 feet long and 1½ feet wide and weighing about 580 pounds including the static loading weight 33 of about 160 pounds, was provided with a pair of rotors 17, 18 inducing about 4700 pounds force at a vibration rate of 2200 V. P. M. and a shoe lift of about $\frac{1}{16}$ inch. Over operating ranges of 2000-2800

V. P. M. and 16 to 45 feet per minute forward travel of the tractor corresponding to about 1 to 6 second duration of local contact, gravel courses as great as 12 inches in compacted thickness have been worked with compaction efficiencies increased from 50 to 90% above that attained without the spring supported static loading weight. Hence the area that may be compacted in a given time is materially increased and greater compaction densities may be obtained as compared with prior apparatus of similar type.

The individual shoes in the six-shoe apparatus described above vibrated up and down beneath the static loading weights which remained substantially stationary due to inertia, the spring 34 being compressed on the upward swing storing energy which is available to increase the effect of the downward compaction stroke. The shoe maintained ground contact at all times during a vibration cycle, rocking slightly about the axis of mounting 13 positioned behind the line of action of the force resultant of the unbalanced wheels by virtue of the resilient torsional freedom allowed by the rubber thereof, so that, though the forward part of the flat shoe bottom cleared the ground surface by as much as 60% of the maximum stroke, contact was maintained at the rear as indicated by the reference lines in Fig. 1.

30 I claim:

1. A road working apparatus comprising a vehicle; a shoe structure having a surface adapted to slide on the ground; an arm structure carrying the shoe and pivoted to the vehicle on a horizontal axis for mounting the shoe on the vehicle for movement relative thereto in a vertical plane parallel to the direction of vehicle movement; a pair of similar eccentrically weighted gear wheels mounted on the shoe by transverse shafts and meshed to rotate at equal speeds in opposite senses, the shafts of said wheels being mounted parallel in a common plane which is substantially parallel to the centerline of said arm when in operative position and the eccentric weights of the wheels being oppositely rotationally positioned relative to each other to substantially counterbalance one another in the direction parallel to the centerline of said arm, whereby when the wheels are rotated at high speeds the major force components developed by the eccentrically weighted wheels act in a direction generally normal to the centerline of said arm; means for driving the unbalanced wheels; a loading weight resiliently supported on said shoe and centered above said wheels with its center of mass in a line normal to the plane through said shafts and midway therebetween; transverse pivot means on the upper portion of said shoe pivotally supporting said mass on said shoe, said pivot means including resilient bushings operatively disposed between said weight and shoe to restrain upward movement of said weight relative to said shoe, the restraint increasing with increase of said upward movement; and compression spring means resiliently supporting said weight on the shoe, the axis of said spring means being disposed in the said normal line.

2. A road base compacting apparatus comprising a tractor machine; a shoe structure having a bottom surface adapted for support by and sliding engagement with the surface of a road base; an arm carrying the shoe and pivoted to the tractor machine on a horizontal axis for vertically movably mounting the shoe thereon, said arm being inclined relative to the road base surface when

in shoe operating position; an actuating mechanism mounted on the shoe for vibrating the shoe in a plane normal to the road engaging surface of the shoe and parallel to the direction of movement of said tractor machine, said mechanism comprising two similar coplanar eccentrically weighted meshing gear wheels mounted on the shoe by transverse parallel shafts lying in a plane which is substantially parallel to said arm when in operative position, the wheels being meshed with the mass centers thereof oppositely rotationally positioned relative to each other so that the forces created by rotation of the wheels are additive in a direction generally normal to the said arm and opposed in a direction parallel thereto; and loading means for the shoe including a weight resiliently supported on said shoe and centered above said wheels with its center of mass in a line normal to the plane through said shafts and midway therebetween, said weight being carried by a second arm pivotally mounted to said shoe with the pivot axis disposed above and transverse to the first said arm, pivot means mounting the second arm to said shoe including a torsionally resilient element torsionally stressed by movement of the second arm to yieldingly restrain movement of said weight away from said shoe,

and compression spring means interposed between the weight and the shoe structure coaxial with said normal line supporting the weight relative to the shoe.

- 5 3. A road base compacting apparatus as described in claim 2, including a plurality of said shoes with corresponding shoe mounting arms in parallel relation across the front of said tractor machine, a beam member extending across 10 the front of and fixed to the tractor having pivot brackets pivotally mounting the shoe arms for independent vibratory movement of the shoes, power means on the tractor for driving the shoe actuating mechanisms, and mechanical power 15 transmission means connecting the power means and actuating mechanism of each shoe.
